(57) **CLAIM**

The ornamental design for a hinge connector for frames for glasses, as shown and described.

DESCRIPTION

FIG. 1 is a prospective view of the hinge connector for frames for glasses showing my new design, the frame for glasses shown in broken lines for illustrative purposes only and forms no part of the claimed design;

FIG. 2 is a front elevational view thereof;

FIG. 3 is a right side elevational view thereof;

FIG. 4 is a rear elevational view thereof;

FIG. 5 is a left side elevational view thereof; and,

FIG. 6 is a top plan view thereof, the bottom plan view being a mirror image thereof.
